ABSTRACT

An apparatus for inserting terminals into a logic plate having a grid of apertures to enclose the terminals including a screen adjacent the lower side of the plate to prevent the terminals from falling through the plate. The plate and screen are supported on a frame that is connected to a means for vibrating the frame. A means is connected beneath the screen for causing a greater atmospheric pressure above the plate than below it. As the frame is rapidly vibrated with sufficient amplitude to cause the terminals to stand on their ends, a vacuum means is applied beneath the plate to assist in drawing the terminals into the apertures.

APPARATUS FOR INSERTING TERMINALS IN AN APERTURED PLATE

BACKGROUND OF THE INVENTION

This invention relates to the field of article handling. In manufacturing logic plates it is necessary to insert a large number of terminals into the apertures of each plate. Previously, the terminals were loaded into the apertures by hand, requiring an excessive amount of time, generally 2 to 4 hours.

SUMMARY OF THE INVENTION

The present invention provides an apparatus to vibrate the plate vertically with sufficient amplitude to cause the terminals to stand on end. At the same time a vacuum is applied to the underside of the plate to draw the terminals into the apertures of the plate.

The invention may be better understood from the following detailed description taken in conjunction with the accompanying drawing.

BRIEF DESCRIPTION OF THE DRAWING

The single FIGURE shown in the drawing is a sectional perspective view of the apparatus.

DESCRIPTION OF THE PREFERRED EMBODIMENT

Reference numeral 1 indicates a plate having a grid of apertures 3 that are to be filled with elongated terminals 5 randomly placed on the top of the plate. The apertures enclose the terminals and extend through the plate and have a 45° counterbore 7 at their upper end to assist the terminal entry into the apertures. A screen 9 is located adjacent the lower

side of the plate to prevent the terminals from falling through the plate as they are loaded therein. Frame 11 includes a ledge 13 to support the plate and screen in position and a duct 15 provides communication between a vacuum creating means 17 and the underside of the plate. The vacuum means creates a greater atmospheric pressure above the plate than below it thus aiding entry of the terminals into the apertures. An arm 19 is attached to frame 11 and is operatively connected to vibrating means 21.

10 When the arm is vibrated with sufficient amplitude the terminals are caused to stand on their ends. By simultaneously applying a vacuum on the underside of the plate the terminals are drawn into the apertures.

I claim:

15 1. An apparatus for insertion of terminals in a plate having a grid of apertures to enclose the terminals comprising:

means for supporting the plate, means for vibrating the supporting means to aid the insertion of terminals in the plate, and means for providing a differential pressure through the plate to further aid the insertion of the terminals in the plate.

20 2. An apparatus for insertion of terminals in a plate having a grid of apertures to enclose the terminals comprising:

means for supporting the plate, means for vibrating the supporting means to aid the insertion of terminals in the plate, means for providing a differential pressure through the plate to further aid the insertion of the terminals in the plate, said supporting means including: an arm for engagement with said vibrating means; a ledge and a screen supported on said ledge adjacent the lower side of said plate to prevent passage of terminals therethrough.
